(57) **CLAIM**

The ornamental design for a display panel with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

1. Display panel with animated graphical user interface

1.1 : Front

1.2 : Front

The appearance of the transitional image sequentially transitions between the images shown in reproductions 1.1-1.2. The process or period in which one image transitions to another image forms no part of the claimed design.

The broken lines represent portions of the display panel with animated graphical user interface that form no part of the claimed design.

**1 Claim, 2 Drawing Sheets
(2 of 2 Drawing Sheet(s) Filed in Color)**
